WALL AND CEILING COVERING.

No. 19,600.

Patented Jan. 21, 1890.

UNITED STATES PATENT OFFICE.

CHARLES CONSTANTINE HISCOE, OF NEW YORK, N. Y., ASSIGNEE TO
FREDERICK BECK, OF SAME PLACE.

DESIGN FOR A WALL AND CEILING COVERING.

SPECIFICATION forming part of Design No. 19,600, dated January 21, 1890.

Application filed December 26, 1889. Serial No. 335,040. Term of patent 3½ years.

To all whom it may concern:

Be it known that I, CHARLES CONSTANTINE HISCOE, a citizen of Great Britain, residing at New York, in the county of New York and State of New York, have invented and produced a new and original Design for a Wall and Ceiling Covering, of which the following is a specification, reference being had to the accompanying drawing, forming part thereof.

10 The leading feature of my design consists of a central portion forming a circle, figure 1, having a central rosette, figure 2, having an inner circle of rosettes, figure 3, the inner size of main circle having rosettes of two sizes, figures 4 and 5. Here is also a continuous ribbon design forming circles, ovals, and other patterns, figure 6, with an ornamentation of

15

rosettes, figures 7 and 8. There is an upper border of lines, figure 9, and rosettes, figure 10, placed at regular distances. The lower border is ornamented by a continuation of ribbon from central part, forming a key-shaped pattern, figure 12, having rosettes for ornaments, figure 13.

What I claim is—

25 The design for a wall and ceiling covering herein shown and described, consisting of ribbon-shaped pattern with ornamentation of rosettes.

CHARLES CONSTANTINE HISCOE.
